UNITED STATES PATENT OFFICE.

ADOLPH TODE, OF MONROE, NEW YORK.

SLED.

SPECIFICATION forming part of Letters Patent No. 407,798, dated July 30, 1889.

Application filed June 4, 1889. Serial No. 313,087. (No model.)

To all whom it may concern:

Be it known that I, ADOLPH TODE, of Monroe, Orange county, New York, have invented an Improved Sled, of which the following is 5 a specification.

This invention relates to a sled so constructed that it will firmly hold the two feet of a standing passenger, who may propel himself by means of a boat-hook over the ice or 10 snow.

The invention consists in the various features of improvement, more fully pointed out in the claims.

In the accompanying drawings, Figure 1 is 15 a perspective view of my improved sled, showing it in use. Fig. 2 is a side view of the sled; Fig. 3, a top view thereof; Fig. 4, a side view of a modification; and Fig. 5 shows the lower part of the boat-hook used for propelling the 20 sled.

The letters *b* represent the two runners of a sled, connected by a series of cross-pieces *a*, that constitute the foot-boards. These foot-boards are received by mortises cut into the 25 upper edge of runners *b*, and are properly secured to such runners by screws *c*. The runners *b* are turned upward and backward at their forward ends to form the rearwardly-extending lips *b'*, projecting over the foremost foot-board. Between these lips and the 30 upper edge of runners *b* a V-shaped recess *b''* is formed of a size to receive the tip or forward part of a shoe.

In use the rider stands with both feet upon the sled, so that his feet project into the recesses *b''*, which securely hold him in place. The weight of the rider will be directly supported upon the runners *b*, which are of course best adapted to sustain it. The rider then propels himself forward with an ordinary boat-hook *A*. 35

It will be seen that a boy can readily mount or leave the sled by simply stepping on or off. When he wishes to drag the sled behind him, he pulls it along by the hook *A'*, which he 40 slips over a cross-bar *d*, connecting lips *b'*.

In Fig. 4 the sled is provided with a pair of rollers *e*.

What I claim is—

1. A sled having its runners turned upward 50 and backward at their forward ends to form a pair of foot-receiving recesses above the foot-board, substantially as specified.

2. The combination of mortised runners *b* with foot-boards *a*, received by the mortises, 55 the runners *b* being turned upward and backward at their forward ends to form the lips *b'*, and the recesses *b''*, above the foot-board, substantially as specified.

ADOLPH TODE.
